NECKTIE HOLDER

Albert O. Skivenes, Chicago, Ill.

Application July 2, 1949, Serial No. 102,726

1. Claim. (Cl. 2—153)

1 This invention relates to necktie holders and, more particularly, to a tie holder formed of a single piece of resilient wire bent into a shape whereby there is provided a frame for supporting the knot portion of a tie intact whether the tie is being worn or held ready for use.

Another object of this invention is to provide a necktie holder capable of maintaining a neat and attractive appearance of the necktie whether it is being worn or held ready for use.

Another object of this invention is to provide means whereby the wearer may put on a previously tied necktie without materially disturbing or disarranging the already tied knot.

A still further object of this invention is the provision of a necktie holder adapted to prevent the knot portion of a necktie from slipping away from the neck or collar of the wearer and thereby creating a sloppy appearance.

A still further object of this invention is to provide a necktie holder adapted to permit ready adjustment of the diameter of the neck-surrounding loop of the necktie without materially disarranging or disturbing the neat appearance of the knot which had been previously tied and supported upon the necktie holder.

A still further object of this invention is to provide a necktie holder adapted to prevent an enlargement of the neck-surrounding loop of the necktie while the tie and supporting holder is being worn.

A still further object of this invention is to provide a necktie holder having a frame adapted to hold the knot portion of a necktie spaced apart from the neck or collar of the wearer.

A still further object of this invention is to provide a necktie holder having a frame adapted to direct the knot portion of the necktie and the upper portion of the front flap of the necktie immediately adjacent thereto downwardly and outwardly from the neck or collar of the necktie wearer.

Further objects and advantages of this invention will become apparent from the following description taken in connection with the accompanying drawings and the appended claim.

In carrying out this invention in one form, there is provided a single piece of resilient wire bent to form a central section adapted to support the knot portion of a necktie, and a pair of wing sections diverging upwardly and rearwardly from the central section. The wing sections are adapted to embrace the neck band of the wearer's collar. Means are provided at the outer ends of the wing sections for subtending a neck-surrounding loop of the necktie.

The central section comprises a nose section and a bridge section. The nose section, adapted to give a predetermined profile to the knot portion of a subtended necktie, is formed of two

5 nose segments converging downwardly from adjacent the ends of the single piece of wire, the ends thereof being twisted upon each other at a point of intersection whereby one end of the wire constitutes a downwardly extending pin. When the necktie and supporting holder are worn, the pin is made to pierce the back flap of the tie to prevent the knot from slipping away from the neck of the wearer.

10 The bridge section, adapted to support the knot portion of a necktie, comprises a horizontal segment substantially spanning the gap between the inner ends of the wing sections, and a spacer section including a loop located in a plane which 15 substantially horizontally bisects the horizontal segment and which also substantially bisects the angle formed by the intersection of the downwardly converging segments of the nose section. The spacer section holds the knot portion of the necktie spaced apart from the neck or collar of the wearer.

One end of the horizontal segment is joined to one wing section by a rearwardly extending reverse bend adapted to limit the slippage of the necktie along the wing section and the horizontal segment. 25 The spacer section is joined to the opposite wing section by a rearwardly extending Z-shaped segment, which serves to limit the slippage of the necktie along the opposite wing section.

30 In accordance with a further embodiment of this invention, the bridge section is modified by eliminating both the horizontal segment spanning the gap between the inner ends of the wing sections and the rearwardly extending reverse bend connecting one of the wing sections to the bridge section. In lieu thereof, a downwardly and inwardly converging wing segment of one wing section has been extended and joined directly to the spacer section. The elimination of the horizontal segment provides for greater resiliency of the tie holder and permits tying and supporting a tie having a knot portion of lesser width and bulk.

45 For a more complete understanding of this invention, reference will be made to the accompanying drawings wherein

Fig. 1 is a front perspective view of the tie holder;

Fig. 2 is a profile view;

Fig. 3 shows the tie holder in plan;

Fig. 4 is a front perspective view of the tie holder showing a necktie partially broken away to indicate the manner in which it is tied and supported upon the holder; and

Fig. 5 is a front perspective view of a modified form of the invention wherein the horizontal segment of the bridge section has been eliminated.

With particular reference to Figs. 1, 2, and 3, 60 one form of the necktie holder comprises a sin-

gle piece of resilient wire (not numbered), such as piano wire, bent to form a central section 10 and a pair of wing sections 12 and 13 diverging upwardly and rearwardly therefrom. Central section 10 comprises a nose section 11 and a bridge section 14. Bridge section 14 consists of those segments of the wire included between the points *a* and *b* and comprises a horizontal segment 17, a spacer section 15, and a Z-shaped segment 29.

Wing sections 12 and 13 each comprise a pair of wing segments 18 and 27, and 19 and 28, respectively, adjacent the ends of horizontal segment 17 and extending outwardly and rearwardly therefrom. Rear wing segments 27 and 28 are bent back upon themselves at the ends thereof remote from horizontal segment 17 to form substantially closed loops 8 and 9, determining apertures 21 and 22 respectively. Forward wing segments 18 and 19 are bent toward rear wing segments 27 and 28, respectively, at points remote from horizontal segment 17, to form reverse bends 23 and 24 which comprise portions of loops 8 and 9 respectively.

The inner end, point *b*, of rear wing segment 28 is joined to one end of horizontal segment 17 by rearwardly extending reverse bend 30, as shown in Fig. 3. Rear wing segment 27 is joined to the other end of horizontal segment by rearwardly extending Z-shaped segment 29 and spacer section 15, as shown in Fig. 1. Z-shaped segment 29 consists of that portion of the wire included between points *a* and *d*, Fig. 1. Spacer section 15 consists of that portion of the wire included between the points *c* and *d*, and comprises a vertical forward spacer segment 16, and a rear spacer segment 31 connected to and extending upwardly and rearwardly from the lower end of forward spacer segment 16 to form V-shaped aperture 32. Spacer segments 16 and 31 lie in a plane (not shown) which substantially perpendicularly bisects horizontal segment 17.

As shown in Fig. 1, Y-shaped nose section 11 is formed of two nose segments 25 and 26 converging downwardly and forwardly from adjacent the ends of horizontal segment 17 and being twisted upon each other at a point of intersection 19 whereby one end of the wire constitutes a downwardly extending pin 20. The upper ends of nose segments 25 and 26 are joined, at points *g* and *h*, to the inner ends of forward wing segments 18 and 19, respectively, the angle of divergence of forward wing segments 18 and 19 being greater and more rearwardly inclined than the angle of divergence of nose segments 25 and 26.

Forward spacer segment 16 of spacer section 15 and nose segments 25 and 26 lie substantially in the same plane (not shown), and the plane in which forward spacer segment 16 and rear spacer segment 31 lie substantially bisects the angle formed at intersection 19 by nose segments 25 and 26, as best shown in Fig. 3.

Necktie 50 is tied about and supported by the necktie holder in the manner shown in Fig. 4, wherein dotted arrows indicate the direction in which rear flap 52 of tie 50 is threaded. Solid arrows indicate the direction of the subsequent threading of forward flap 51 to form a conventional four-in-hand knot 55 using the tie holder as a frame.

As illustrated, rear flap 52 is first inserted rearwardly through aperture 21, determined by loop 8, then forwardly through aperture 22, determined by loop 9, so as to suspend a neck-surrounding loop portion 53 of tie 50 between and

5 rearwardly of loops 8 and 9, then transversely from right to left in front of nose segment 26 and through aperture 32 in spacer section 15, after which it is permitted to dangle. The length of rear flap 52 below aperture 32 and the suspended length of neck-surrounding loop portion 53 are adjustable to meet the requirements of the particular wearer (not shown).

10 Front flap 51 of tie 50 is then wound about the tie holder to form the conventional four-in-hand knot 55 shown loosely tied and partially broken away in Fig. 4. Commencing just forwardly of aperture 21, front flap 51 is first passed transversely from left to right and forwardly of the dangling rear flap 52, rearwardly of nose segment 25, forwardly of forward spacer segment 16, and rearwardly of nose segment 26, then forwardly and upwardly in front of nose segment 26, then rearwardly over horizontal segment 17, then downwardly through neck aperture 56 keeping to the right of spacer segment 31, then forwardly under wing section 13 and to the right of nose segment 26, then transversely from right to left and forwardly of nose section 11 to form the crosspiece portion 54 of the knot 55, then rearwardly under wing section 12 and to the left of nose segment 25, then upwardly through neck aperture 56 keeping to the left of spacer segment 31, then forwardly over horizontal segment 17, and then downwardly between nose section 11 and crosspiece portion 54 thereby completing the four-in-hand knot 55.

25 After the knot 55 has been formed upon the necktie holder, the tie 50 may be put on the wearer by adjusting neck aperture 56 to slip over the head of the wearer (not shown). This adjustment may be made by pulling rear flap 52 rearwardly through aperture 22, thereby increasing the neck-surrounding loop portion 53 of the tie. After dropping the loop portion 53 over the head of the wearer, neck aperture 56 may be decreased in diameter by pulling rear flap 52 forwardly through aperture 22 until the tie 50 is comfortably and neatly positioned about the neck of the wearer with the dangling forward and rear flaps 51 and 52 in a desired relationship to each other. Once secured on the neck of the wearer, the knot 55 and supporting tie holder are prevented from slipping away from the neck of the wearer by piercing rear flap 52 of the tie 50 with the pin or stem portion 20 of the Y-shaped nose section 11. Z-shaped segment 29 and reverse bend 30 act as limit stops to prevent slippage of the tie 50 on wing sections 12 and 13, respectively. Spacer section 15 holds the knot portion 55 spaced apart from the neck of the wearer, and nose section 11 gives the knot portion 55 a profile contour directed downwardly and outwardly from the neck of the wearer.

30 It is to be understood that the lengths of the various segments of the single piece of wire may be varied to suit the taste of the wearer and the size and shape of the tie to be used. For example, the width of the knot 55 may be varied by changing the length of the horizontal segment 17. The profile contour of the knot 55 and of the upper portions of the tie adjacent thereto may be varied by changing the length, degree of divergence, and the curvature of nose segments 25 and 26. Further, instead of using a single piece wire, the tie holder could be formed of a plurality of separate segments joined end to end to form the configuration disclosed.

35 In a modified form of this invention shown in Fig. 5, the previously described horizontal seg-

ment 17 has been eliminated to give the tie holder greater resiliency and to permit tying and supporting a tie having a narrower knot portion. This embodiment comprises a bridge section 40, a pair of wing sections 12 and 13 diverging upwardly and rearwardly from adjacent the ends of the bridge section 40, and a nose section 11 converging downwardly and forwardly from adjacent the ends of the bridge section 40. Wing sections 12 and 13, and nose section 11 are substantially similar to those of the first embodiment shown in Figs. 1 through 4.

Bridge section 40 consists of that portion of the single piece of wire (not numbered) extending between points *e* and *f*, and comprises a spacer section 15, a rearwardly extending Z-shaped segment 29 and a link 41, the link 41 being a downward and inward extension of rear wing segment 28. Rear spacer segment 31 of spacer section 11 is joined to rear wing segment 27 by Z-shaped segment 29 as in the previous embodiment. The upper end of forward spacer segment 16 is joined to the inner end of rear wing segment 28 by link 41 extending therebetween. As in the prior embodiment, the plane (not shown) containing spacer section 11 substantially bisects the angle formed by converging nose segments 25 and 26.

A necktie may be tied upon the embodiment shown in Fig. 5 in substantially the same manner as described heretofore and shown in Fig. 4, since connecting link 41 and horizontal portion 35 of Z-shaped segment 29 are adapted to support the knot portion of a necktie in substantially the same manner as horizontal portion 17 provided in the prior embodiment.

It will be apparent from the foregoing that many changes and modifications may be made in the structure described in the foregoing without departing from the spirit and scope of this invention. While two particular embodiments are disclosed above, it will be understood, of course, that the invention is not to be limited thereto since

many modifications may be made and it is contemplated therefore, by the appended claim, to cover any such modifications as fall within the true spirit and scope of the invention.

5 I claim:

A necktie holder of the class described formed of a continuous piece of wire comprising a central section for supporting the knot portion of a necktie, a pair of wing sections each including upper and lower wing segments diverging upwardly and rearwardly of said central section, said central section comprising a nose section formed by downwardly and forwardly converging extensions of said upper wing segments, the ends of said extensions being joined and including a downwardly extending pin adjacent thereto, said central section also comprising a spacing section formed by joining extensions of said lower wing segments so as to form a continuous loop in a plane substantially bisecting the angle of divergence of said wing sections and substantially perpendicular to the plane defined by said nose section, said loop having a forward segment lying substantially in said last mentioned plane and a segment spaced rearwardly of said plane, and means at the ends of said wing sections remote from said central section for subtending a neck-surrounding loop in said necktie.

ALBERT O. SKIVENES.
